Primary Examiner—Louis S. Zarfas*Assistant Examiner*—Robert A. Delehanty*Attorney, Agent, or Firm*—Goldstein & Canino**[57]****CLAIM**

The ornamental design for a finger protection device, as shown and described.

DESCRIPTION

FIG. 1 is a diagrammatic perspective view of a finger protection device in full lines with a hand shown in broken lines representing environmental association matter being for illustrative purposes only and forming no part of the claimed invention.

FIG. 2 is a front elevational view of the finger protection device.

FIG. 3 is a rear elevational view thereof.

FIG. 4 is a left side elevational view thereof.

FIG. 5 is a right side elevational view thereof.

FIG. 6 is a top plan view of the finger protection device; and, FIG. 7 is a bottom plan view thereof.
